INVENTOR

George Z. Clark,

UNITED STATES PATENT OFFICE.

GEORGE Z. CLARK, OF TOPEKA, KANSAS.

LUBRICATOR FOR STEAM MACHINERY.

SPECIFICATION forming part of Letters Patent No. 366,714, dated July 19, 1887.

Application filed April 16, 1887. Serial No. 235,027. (No model.)

To all whom it may concern:

Be it known that I, GEORGE Z. CLARK, of Topeka, in the county of Shawnee and State of Kansas, have invented certain new and useful Improvements in Lubricators for Steam Machinery, of which the following is a specification, reference being had to the accompanying drawings, illustrating my improvements, in which—

10 Figure 1 is a vertical central sectional view of my improved device, and Fig. 2 is a similar view showing a formal modification.

The object of my invention is to provide a simple, reliable, economical lubricator, to be 15 operated by the use of steam, and which may be attached to a steam-cylinder or other parts of steam machinery requiring internal lubrication.

Referring to the letters upon the drawings, 20 A designates an oil-cup, open and internally screw-threaded at both ends.

B designates a cock or faucet, of ordinary character, for draining off the water of condensation.

25 C designates a cross piece or guide for one end of the oil-tube D, supported in the screw-threaded opening X, to hold the tube in its place.

E designates a cap, which screws over the 30 top of the oil-cup, fitting steam-tight. There is a screw-threaded opening through this cap, into which fits the pointed screw-pin F, the point of the pin entering an opening in the upper end of the oil-tube D. This oil tube has an enlarged end or collar, L, at the bottom, having its seat made tight with a ground joint at M, in the ordinary way.

G designates a nut, which screws down upon the top of the cap E, and fits tightly around 40 the smooth part of the pin F.

H is a plug or stopper for the lower end of the oil-cup, which screws into it, as illustrated. This plug is externally screw-threaded at I on its lower end for the purpose of attaching the 45 lubricator to a steam-cylinder or other part to be internally lubricated. It is also internally screw-threaded to receive the nut K. The oil-tube being inserted from the bottom in place, the nut K is screwed up, so as to press the enlarged end of the tube firmly and steam-tight against its seat at M, so that the opening through the nut will form a continuation of the

oil-tube. To supply the cup with oil, the top cap, E, holding the pin, should be unscrewed, so as to permit oil to be poured in at the opening X and partly fill the oil-cup, as indicated. Then the cap E should be screwed down, and the pin F should be adjusted to admit more or less oil into the tube D, according to the amount of lubrication desired. Then, when 50 steam is on, it will enter through the nut K, through the tube D, and pass into the upper part of the oil-cup, where it will condense, and the water of condensation will settle to the bottom of the cup, raising the oil to the top, 55 where it will overflow around the point of the pin into the oil tube and drip down through it to the interior of any machinery to which the lubricator may be attached.

In Fig. 2, where a modification of my lubricator is shown, the plug H is internally screw-threaded at its upper end at N, and a steam-tight joint is formed at O, the position of the enlarged end of the oil-tube being reversed, so that it will fit down upon the seat at O, as 70 shown. The plug H is internally screw-threaded at its upper end to receive the nut Q, which forces the enlarged end L' of the tube down on its seat. This is a formal change, in which I also use a nut with a hole through it 75 for forcing the tube to place upon its seat.

I am aware that it is not new to lubricate machinery internally by raising oil and dripping it through the process of condensing steam within an oil-receptacle, and I do not 80 claim that; but

What I claim, and desire to secure by Letters Patent of the United States, is—

In a lubricator for steam machinery, the combination, with an oil-cup, A, open at both 90 ends and provided with screw-threaded stoppers, of the oil-tube D, provided with a collar or enlarged lower end seated steam-tight upon the plug H, a nut with an opening through it for securing the tube firmly to its 95 seat, the pointed screw-pin F, to regulate the flow of oil into the tube D, and the nut G, substantially as set forth.

In testimony whereof I have hereunto subscribed my name.

GEORGE Z. CLARK.
